UNITED STATES PATENT OFFICE.

MORTON HALBERT MEGAFFIN, OF EDGEWOOD, IOWA.

FOLDING LANDING-GEAR FOR AEROPLANES.

1,333,329.

Specification of Letters Patent.

Patented Mar. 9, 1920.

Application filed September 15, 1919. Serial No. 323,708.

To all whom it may concern:

Be it known that I, MORTON H. MEGAFFIN, a citizen of the United States, and a resident of Edgewood, in the county of Clay-
5 ton and State of Iowa, have invented a new and useful Improvement in Folding Landing-Gears for Aeroplanes, of which the following is a full, clear, and exact description.

My invention relates to improvements in
10 folding landing gears for aeroplanes, and it consists in the combinations, constructions, and arrangements herein described and claimed.

An object of my invention is to provide a
15 folding landing gear which may be folded when the machine is in the air but which may be released at will, to assume a position for landing.

A further object of my invention is to
20 provide means for positively locking the landing gear in its folded position and also in its extended position.

A further object of my invention is to provide a simple device for accomplishing
25 the above named objects which may be readily applied.

Other objects and advantages will appear in the following specification, and the novel features of the invention will be particularly pointed out in the appended claim.

My invention is illustrated in the accompanying drawings, forming part of this application, in which—

Figure 1 is a side view of the portion of
35 an aeroplane provided with my improved folding landing gear.

Figs. 2, 3, and 4 are diagrammatic views showing the various positions of the landing gear.

40 Fig. 5 is a section along the line 5—5 of Fig. 1.

Fig. 6 is a sectional detail view showing a slidable connection for one of the supporting struts.

45 Fig. 7 is a detail view showing an elevating lever.

In carrying out my invention, I make use of an aeroplane body 1 of any suitable type. Mounted on bottom frame pieces 2, are

50 brackets 3 (see Fig. 5) having bearing supports 4 for pivot pins 5 to which are secured hangers 6 for wheels 7. The bottom part of each hanger is connected by a hinge 8 with a strut or brace member 9. The upper end 55 of each brace member 9 is pivotally connected with a slidable block 10 which is disposed in

a groove 11 of the frame member 2, as is shown in Fig. 6. This block is slidable in the groove and is provided with two recesses 12 and 13 which are arranged to receive the 60 locking fingers 14 and 15 of pivoted locking members 16 and 17 respectively. The pivoted locking member 16 is connected by a link with a lever 19 disposed in the cock pit of the aeroplane, while the pivoted locking member 17 is connected by a link 20 with a lever 21. The lever 22 is mounted on a pivot and a link 23 is connected eccentrically at one end to the lever 22 and at the other end to the hanger 6.

70 From the foregoing description of the various parts of the device, the operation thereof may be readily understood. Fig. 1 shows the landing gear in position for use. In this position it will be observed that the 75 finger 14 of the block 10 is in the recess 12, thus locking the landing gear in position. After the aeroplane is in flight, the landing gear may be folded by pushing forwardly on the lever 19, thus rotating the pivoted 80 locking member 16 and withdrawing the finger 14 from the notch or recess 12. The lever 22 may now be pulled in the direction indicated by the arrow, thereby swinging the hangers 6 and the strut 9 into the dotted 85 line position indicated in Fig. 1. When the block 10 reaches the finger 15 of the pivoted locking member 17, the finger will enter the recess 13, thus locking the block in position. The landing gear will now be in the position, shown diagrammatically in Fig. 2, being moved from the position shown diagrammatically in Fig. 4, through that shown in Fig. 3.

90 When it is desired to land, all that is necessary is to push rearwardly on the lever 21 whereupon the pivoted locking member 17 will be swung so as to bring the finger 15 out of the recess 13 and the block 10 being thus freed, will move forward in the 95 groove under the weight of the landing gear until it reaches the pivoted locking finger 14 which will enter the groove 12, thus locking the landing gear in position for landing.

100 I claim:

105 The combination with an aeroplane of pivoted hangers carried thereby, wheels secured to said hangers, struts hinged to the bottom portion of said hangers, slidable blocks connected with the upper ends of 110 said struts, frame members provided with grooves arranged to receive said blocks, a

rigid link connected at one end to the said hangers and at the other end to a lever in the cock pit of the aeroplane for swinging the lower end of said hangers upwardly, thereby sliding said blocks in the grooves in said frame members, pivoted locking members connected by rigid links to levers in the

cock pit of the aeroplane for locking said blocks at the ends of the line of travel in said grooves and for unlocking the said blocks at will to permit the lower ends of said hangers to be swung downwardly by the force of gravity.

MORTON HALBERT MEGAFFIN.
